UNITED STATES PATENT OFFICE

2,609,959

BAKE PAN UNIT

Jesse L. Darnell, Milford, and Elbert M. Cormack, Mount Healthy, Ohio, assignors to The Lockwood Manufacturing Company, Cincinnati, Ohio, a corporation of Ohio

Application June 9, 1949, Serial No. 98,084

7 Claims. (Cl. 220—23.2)

1

This invention relates to baking pan units of the type disclosed in prior Patents Nos. 2,037,759, 2,143,728, and 2,198,105 issued to Elmer H. Chandonia, and more particularly to improvements in the means whereby the pans are secured to the straps or bands of the unit.

Pan sets for bakers usually comprise a plurality of individual pans arranged in side by side or parallel relationship and secured together as a unit by means of a band that embraces the pan unit and is secured to the individual pans. The number of pans in a set, the space between pans, and the size and shape of individual pans are usually specified by the baker. The baker also may specify his choice of type of band, some preferring the over-wire band and others the under-wire band.

An object of this invention is to provide a pan-set construction having a vertical lap clinch for both over-wire and under-wire banded pan-sets.

Another object of the invention is to provide a rivetless pan-set with an improved vertical clinch between the pans and the bands for both the over-wire and the under-wire band type.

These and other objects of the invention will in part be apparent and will in part be obvious from the following description, taken in conjunction with the accompanying drawings, in which:

Figure 1 is a fragmentary view of a pan-set as seen looking at the ends of pans in a unit provided with the over-wire band and embodying a vertical clinch arrangement in accordance with a form of the invention whereby the individual pans are rigidly secured at the ends thereof to the band;

Fig. 2 is an enlarged sectional view taken on line II—II of Fig. 1;

Fig. 3 is a view in elevation of a portion of the over-wire band shown in Fig. 1;

Fig. 4 is a view in section taken on line IV—IV of Fig. 3;

Fig. 5 is a view in perspective of one end of a pan such as shown in Fig. 1;

Fig. 6 is a view in section taken on line VI—VI of Fig. 1;

Fig. 7 is a view similar to Fig. 1, of an under-wire band construction embodying the vertical clinch of the invention;

Fig. 8 is a view in side elevation of a pan unit showing how the bands at the opposite ends of the pan unit are tied together by means of a strap;

Fig. 9 is a top plan view of a pan-set such as shown in the preceding views;

Figs. 10 and 11 are views showing modified

forms of bands containing vertical lap clinch lugs.

Throughout the drawings and the specification like reference characters indicate like parts.

- 5 In Fig. 1 of the drawings we have shown a portion of the pan-set which comprises a plurality of pans 10, only two of which are shown, in end view. These pans are spaced apart a predetermined or specified distance and are rigidly secured at their ends to a band 11. The band 11 may comprise two sections, one at each end of the pan set, with the ends of the bands tied together by means of straps 12 which are riveted to the bands as indicated at 13 in Figs. 8 and 9. 10 The straps 12 may be omitted and the ends of the band sections 11 may be riveted or otherwise secured to the outer walls of the outermost pans as shown at R in Fig. 11, or there may be a continuous peripheral or embracing band 11' having the same shape in section as sections 11, 15 the ends of which overlap as at R' at the outer wall of one of the outermost pans, the overlapping ends being riveted or otherwise secured as shown in Fig. 10. 20

- 25 The opposite ends of the pans of a unit are rigidly and firmly secured to the bands 11 by means of a vertical clinch 14.

- The pans 10 of these units are of usual construction. As is customary, each pan is made from a sheet of tin plate which has been blanked in the flat in such a manner that when the metal is folded, a pan having ends and sides is formed. The ends of the pans, as will be observed from the drawings, have, as a result of the folding, inverted triangular flaps 15, and these flaps are 30 of double thickness. Behind the inverted triangular flaps 15 there is a single thickness end wall 16 at each end of the pan. The end walls 16 and the side walls of the pan project above the base lines 17 of the triangular flaps.

- 35 As may be seen by inspection of Figs. 1 and 5, an L-shaped notch 18 is cut in the free corners of the triangular flaps 15, so that these corners can be bent or deflected outwardly from the end walls 16 after the pans have been completely

- 40 formed. The pans shown are of the type having a reinforcing wire 20 extending around the periphery of the individual pans at the top thereof and the edges of the sides and ends of the pans are rolled over this wire, the rolled-over edges 45 21 conceal the reinforcing wire 20 and abut the triangular flaps 15 between the shoulders 28 of the notches 18 and the outer corners of the

individual pans. Thus, as stated, the free corners of these triangular flaps 15 may be bent outwardly away from the end walls 16 when the band is to be applied thereto.

The end bands 11, as shown, are formed with half-round grooves 24 and 25 at their upper and lower edges, respectively, the upper half-rolled groove 24 being deep enough to substantially embrace the rolled edge 21 at the ends and corners of the pans. The lower half-round groove 25 is primarily for the purpose of increasing the stiffness and rigidity of the bands.

Bands 11 are provided with inwardly and downwardly projecting vertical lugs 26 which are formed by partially punching out metal as indicated in the drawings. These lugs are disposed in a vertical plane and extend downwardly below the rim of the pan. As may be seen more particularly in Figs. 2 and 4, the lugs 26 are bent inwardly towards the end walls 16 of the pan in order to accommodate the corners of flaps 15. The lugs 26 are so spaced that when the bands are attached to the pan units, the lugs will fit quite snugly against the vertical shoulders 28 formed at the ends of the notches 18.

The bands are applied to the ends of a series of pans by deflecting the free corners 15' of the triangular folds 15 outwardly from the end walls 16 as indicated in dotted lines in Fig. 5. The bands are then slipped over the top of the pans with the lugs 26 placed behind the corners of flaps 15. By applying pressure to the bands in the regions of the lugs 26, the free corners of the triangular folds or flaps 15 and the lugs 26 are squeezed together and clinched as shown in Fig. 2. When the pans have been attached to the bands 11 in the manner above described the pans are held against movement longitudinally of the bands by the co-action of the lugs 26 and the abutting shoulders 28. Also, by reason of the fact that groove 24 substantially embraces the rolled edges 21 of the pans, the pans are firmly locked to the bands so that they can neither turn about either lug 26 as an axis. The bands 11 having been secured to the ends of the pans as above described, the tie bands 12 are applied as shown in Figs. 8 and 9. The upper edges of bands 12 may if desired be designed to abut the underside of the rolled longitudinal edges of the outermost pans in a unit and are riveted to the bands 11 as indicated at 13.

In the band over-wire construction, the reinforcing wire 20 is usually of larger diameter than the reinforcing wire used on pans having the under-wire band construction shown in Fig. 7. In the over-wire construction the width of the bands 11 may be greater than those shown in Fig. 7. However, the matter of dimension of bands is largely dictated by a particular customer's choice. In any event, these bands are made as heavy or strong as is necessary to give the strength and rigidity required in a pan unit, in view of the rough handling they receive in use.

If the form of bands shown in Figs. 10 and 11 are employed, they are secured to form the vertical lap clinch between the flaps 15 and lugs 26 as above described. In the form shown in Fig. 11, the ends of sections 11 are riveted to the pan walls as shown, or if the continuous band of Fig. 10 is employed, the overlapping ends of the band are secured together as with rivets or by a projection weld.

The strength and rigidity of the triangular flaps 15 and the clinch lugs 26 prevent down-

ward movement of the end bands or band sections in relation to the pan ends, while the interlocking of the bands 11 with the rolled edges of the pan ends and the securing of the ends thereof as shown, prevents upward movement of the bands in relation to the pan ends.

In Fig. 7, we have illustrated how the vertical clinch may be applied to under-wire bands. As there illustrated, the upper half-round groove 24' fits snugly under the wire reinforced rolled edge at the ends and corners of the pans, and the vertical clinch lugs 26 are disposed behind the free corners of the triangular flaps 15, as in Fig. 1. In the under-wire band construction it may be found that the free corners of the triangular flaps 15, when made as in Fig. 1, will be so stiff that they can not be easily bent outwardly to receive the vertical clinch lugs 26 without considerable effort. Therefore, to make it easier to bend these free corners outwardly from the end walls 16 of the pans, an additional notch 30 may be cut in the triangular flaps 15 immediately under the rolled upper edges of the pans.

It is to be observed, also, that the L-shaped notches 18' extend farther down into the free corners of the flaps 15 because the clinch lugs 26 are spaced farther from the rim 21 of the pans when the under-wire bands are applied.

When the bands are applied, the vertical clinch lugs 26 abut the corners 28' in the triangular flaps and the pans can not shift in either direction lengthwise of the bands 11'. As in the over-wire band construction, the clinch lugs and the free corners of the triangular flaps 15 are squeezed together so as to cause the flaps and the lugs and end walls 16, to be firmly and rigidly clinched. Thus, a rigid connection is accomplished by means of the vertical clinch between the ends of the pans and the bands.

Having thus described the invention, it will be apparent to those skilled in this art, that changes may be made in the specific constructions illustrated without departing from the spirit or the scope of the invention. Therefore, what we claim as new and desire to secure by Letters Patent is:

1. In a baker's banded pan-set comprising a plurality of bake pans disposed in side by side relationship, the ends of each pan having a pair of inverted substantially triangular flaps, the bases of which are parallel to and spaced from the tops of said pans, a band at each end of the pans, said bands extending across the ends of all pans in the set and around the outer corners of the outermost pans in said set and having downwardly projecting vertical clinch lugs offset inwardly of the bands, said lugs being disposed between said flaps and the end walls of said pans, and straps disposed along the outer sides of the outermost pans and connected to the ends of the said bands disposed at the opposite ends of said pans, the foregoing pan-set being characterized by the fact that each pan has a wire-reinforced rolled edge at the periphery of the top thereof, that the end bands are provided at their upper edges with a groove adapted to receive the wire-reinforced edges of the pan ends, that the triangular end flaps are provided with notches adjacent the under sides of said reinforced pan edges, and that said vertical clinch lugs extend between said flaps and pan end walls and abut the shoulders of said notches whereby the pans are secured to said bands and locked against movement lengthwise of said bands.

2. A pan-set according to claim 1 characterized by the fact that the free corners of each triangu-

lar flap at each pan end are notched, and that the end bands are provided with two inwardly and downwardly projecting vertical clinch lugs for each pan end, and that the lugs are spaced to interlock with said notches in the free corners of said flaps, the said flap corners and lugs being squeezed together to form a rigid vertical clinch.

3. A pan-set according to claim 1 characterized by the fact that each pan has a wire-reinforced rolled edge at the periphery of the top thereof, that the end bands are provided at their upper edges with a groove adapted to receive the wire-reinforced edges of the pan ends, that the free corners of each triangular flap at each pan end are notched, and that the end bands are provided with two inwardly and downwardly projecting vertical clinch lugs for each pan end, and that the lugs are spaced to interlock with said notches in the free corners of said flaps, the said flap corners and lugs being squeezed together to form a rigid vertical clinch.

4. A pan-set according to claim 1 characterized by the fact that the end bands are provided with stiffening grooves along their longitudinal edges, that the upper edges of said bands abut the under side of the rolled edge at the top of the pan ends, that the triangular end flaps are provided with notches adjacent the under sides of said reinforced pan edges, and that said vertical clinch lugs extend between said flaps and pan end walls and abut the shoulders of said notches whereby the pans are secured to said bands and locked against movement lengthwise of said bands.

5. A pan-set according to claim 1 characterized by the fact that the end bands are provided with stiffening grooves along their longitudinal edges, that the upper edges of said bands abut the under side of the rolled edge at the top of the pan ends, that the free corners of each triangular flap at each pan end are notched, and that the end bands are provided with two inwardly and downwardly projecting vertical clinch lugs for each pan end, and that the lugs are spaced to interlock with said notches in the free corners of said flaps, the said flap corners and lugs being squeezed together to form a rigid vertical clinch.

6. A pan-set according to claim 1 characterized by the fact that the end bands are provided with stiffening grooves along their longitudinal edges, that the upper edges of said bands abut the under side of the rolled edge at the top of the pan ends, that the bands extend across the ends of all the pans in the unit and around the outer corners of the outermost pans of the set, that the free corners of each triangular flap at each pan end are notched, and that the end bands are provided with two inwardly and downwardly projecting vertical clinch lugs for each pan end, and that the lugs are spaced to interlock with said notches in the free corners of said flaps, the said flap corners and lugs being squeezed together to form a rigid vertical clinch.

7. In a baker's banded pan-set comprising a plurality of bake pans disposed in side by side relationship, the ends of each pan having a pair of inverted substantially triangular flaps, the bases of which are parallel to and spaced from the tops of said pans, a band embracing the pan set and engaging the upper portions of the opposite end walls of the individual pans in the set and the upper portions of the outer walls in the outermost pans of said set, the portions of the bands engaging the end walls of said pans being provided with spaced downwardly projecting clinch lugs offset inwardly of the said band sections, there being a lug between each of said flaps and each end wall of a pan, and shoulders on said flaps engaging the outermost sides of said lugs to prevent movement of said pans lengthwise of said band sections.
